Atty.

UNITED STATES PATENT OFFICE.

BERT R. BENJAMIN, OF OAK PARK, ILLINOIS, ASSIGNOR TO INTERNATIONAL HARVESTER COMPANY, A CORPORATION OF NEW JERSEY.

SEAT SPRING.

Application filed November 11, 1920. Serial No. 423,236.

To all whom it may concern:

Be it known that I, BERT R. BENJAMIN, a citizen of the United States, residing at Oak Park, in the county of Cook and State 5 of Illinois, have invented certain new and useful Improvements in Seat Springs, of which the following is a full, clear, and exact specification.

This invention relates to a spring, and 10 more particularly to a seat spring which is used in connection with agricultural implements or similar devices, and has for its object to provide a spring of improved construction whereby the maximum amount 15 or resiliency is derived without affecting the strength and durability of the same.

A further object is to provide a construction of a seat spring which permits a graduating resiliency.

20 A further object is to provide a structure in which the rigidity of the spring is increased at the desired points.

A still further object is to provide a construction of this type of a seat spring in 25 which the amount of material is considerably reduced without affecting the efficiency and increasing the resiliency of the same.

These and other objects are attained by providing a simple and efficient construction 30 hereinafter minutely described and claimed.

In the accompanying drawings I have 35 illustrated one embodiment which my invention may assume in practice. It is to be understood, however, that the form shown herein may be modified without departing from the spirit of my invention.

Fig. 1 is a top plan view of my improved spring.

Fig. 2 is a side elevational view of the same 40 showing the seat attached at the upper end thereof.

Figs. 3, 4 and 5 are cross sectional views taken on the lines 3—3, 4—4 and 5—5 respectively in Fig. 2.

45 Heretofore considerable difficulty has been experienced in making a seat spring of the required resiliency and at the same time retain the strength necessary to prevent the breakage of the same. I have overcome this difficulty by providing a flat steel cantilever spring 10 of uniform cross section preferably made of high carbon steel and having a longitudinally extending embossed bead 11 tapering from the upper end 12 50 to the lower end 13. The gradual increase

in the width and depth of the embossed bead is clearly shown in Figs. 3, 4 and 5 respectively. This obviously increases the stiffness of the spring as the lower end of same is approached. The upper end portion 17 60 of the spring 10 is bent horizontally with respect to the main portion and is provided with two apertures 14 adapted for adjustably fastening a seat 15 shown in the dotted lines in Fig. 2 and the lower end of the 65 spring is provided with an aperture 16 for fastening the spring to any desired implement.

It will be noted from the above description of my improved construction of the 70 seat spring that I have not only overcome the difficulty of making a seat spring of the desired resiliency and at the same time retained the strength necessary to prevent the breaking of the same but also provided an 75 efficient and economical construction in which considerable weight in material is saved and at the same time increasing the strength, durability and resiliency of the spring.

While I have herein described one embodiment of my invention for the purpose of illustration, it is of course to be understood that the same may be modified without departing from the spirit of my invention.

What I claim and desire to secure by Letters Patent is:

1. A flat spring of uniform cross section comprising two angularly disposed portions, one of said portions having an embossed bead therein, said bead being of least depth and least width adjacent the angle between the two portions and gradually diverging to maximum width and maximum depth adjacent its other end.

2. A flat spring of uniform cross section comprising two angularly disposed portions, one of said portions being relatively longer than the other and having an embossed bead therein, said bead being of least depth and least width adjacent the angle between the two portions and gradually diverging to maximum width and maximum depth adjacent its other end.

3. A flat spring of uniform cross section comprising two angularly disposed portions, one of said portions being relatively longer than the other and having a gradually diverging, longitudinally extending, embossed bead therein of both varying width and depth.

4. A flat seat spring of uniform cross section comprising an elongated rectangularly shaped metallic strip having a centrally arranged longitudinally extending embossed bead therein throughout a portion of its length, the bead being relatively wide, shallow and flat at one end and gradually converging and becoming rounded, narrower and deeper at its other end, whereby a graduated resiliency is imparted to the spring when under stress.

5. A seat spring of uniform cross section comprising a flat portion and a beaded

portion, the two portions being angularly disposed with respect to each other, the 15 bead in the one portion being centrally and longitudinally arranged, the bead further being relatively wide, shallow and flat at one end and gradually tapering and becoming rounded, narrower and deeper at its 20 other end, whereby a graduated resiliency is imparted to the spring when under stress.

In testimony whereof I affix my signature.

BERT R. BENJAMIN.
